DESIGN FOR A PLASTIC SHEET OR SIMILAR ARTICLE

Alan F. Harvey, Kearny, N. J., assignor to E. I. du Pont de Nemours & Company, Wilmington, Del., a corporation of Delaware

Application April 2, 1937, Serial No. 68,528

Term of patent 14 years

To all whom it may concern:

Be it known that I, Alan F. Harvey, a citizen of the United States and a resident of Kearny, in the county of Hudson and State of New Jersey, have invented a new, original, and ornamental Design for a Plastic Sheet or Similar Article, of which the following is a specification; reference being had to the accompanying drawing forming part thereof.

In the accompanying drawing:

Figure 1 is a view of a section of a flat plastic sheet or similar article showing my new design; and

Figure 2 is a view of a section of a plastic sheet or similar article bent into the form of a tube and showing my new design.

My design is characterized by a basket-weave arrangement formed by a series of square sections, said sections comprising laminations exhibiting colored and pearl effects. The thickness of the sheet is immaterial.

I claim:

The ornamental design for a plastic sheet or similar article, substantially as shown and described.

ALAN F. HARVEY.
